UNITED STATES PATENT OFFICE

DAVID QUINN, OF EAU CLAIRE, WISCONSIN

MAIL BOX

Application filed July 14, 1928. Serial No. 292,832.

The present invention has reference to a mail object and its prime object is to provide a structure whereby a mail box may be mounted on the outside of a house or the like, and has a lock associated therewith which is operable only from the inside of the house so as to afford access to the mail box.

For instance, it is intended that the box shall be mounted on the exterior wall of a building or analogous structure or any wall accessible to the mail man.

The mail box is constructed so as to provide that it cannot be opened except by operation from within the building and from a point inaccessible to any person other than the owner. It is preferable, of course, that the mail box be mounted adjacent the door, so that the authorized person may release the locking mechanism with one hand and open the door of the mail box with the other.

A still further very important object of the invention resides in the provision of a mail box of the nature which is exceedingly simple in its construction, inexpensive to manufacture, strong and durable, thoroughly efficient and reliable in use, and otherwise well adapted to the purpose for which it is designed.

With the above and numerous other objects in view, as will appear as the description proceeds, the invention resides in certain novel features of construction, and in the combination and arrangement of parts as will be hereinafter more fully described and claimed.

In the drawings:

Figure 1 is a side elevation of the box embodying the features of my invention.

Figure 2 is a front elevation thereof.

Figure 3 is a transverse horizontal section taken substantially on the line 3—3 of Figure 1, and

Figure 4 is a detail vertical section taken substantially on the line 4—4 of Figure 2.

Referring to the drawings in detail, it will be seen that the box is constructed of a bottom 5, a rear wall 6, a side wall 7 at one end of the bottom and rear wall 6, and a front wall 8, rising from the bottom between the forward edges of the side wall 7 and the top 9. The side, which is opened has hingedly mounted

therein, as at 10, a door 11, to swing on a vertical axis. A spring 12 is engaged with the door and when the door is closed engages the front wall 8, and tends to slightly open the door so that it may be readily opened by a person when released, as hereinafter described. The free edge of the door is provided with an L-shaped extension 14. A spring catch 15 is mounted on the rear wall 6 to engage the extension 14 and hold the door in a closed position.

The tube 16 extends from the rear wall 6 through an opening in the supporting wall 17 and slidably supports a plunger 18, which is held in a predetermined position by a spring member 19. This plunger may be pushed inwardly to release the catch 15 from the extension 14, so that the spring 12 will partially open the door so that the door may be readily opened the rest of the way to afford access into the interior of the box. The rear wall 6 is provided with flanges 20 at the upper and lower ends thereof which are screwed to the supporting walls 17 as is indicated at 21. The front wall 8 is provided with a transverse opening 22. A rod 23 extends between the side walls 7 at the upper edge of the opening 22 and rockably supports a closure 24, for the opening 22. This closure has projections 25 to limit the outward movement thereof and is adapted to abut projections 26 on one side wall 7 to limit the inward movement thereof.

As is shown in Figure 3 a deflector wall 28 is provided in the box, with which mail may engage when the closure 24 is forced open so that the mail will be directed downwardly in the box.

From the above detailed description it will be seen that I have devised a box which may be, for example mounted on the wall of the house adjacent the front door.

The mail carrier may place the mail in the box and the owner of the house may open the door 11 by pressing in on the plunger 18 from the inside of the house and then come out and complete the opening of the door 11. Obviously, the mail box may be used in many other different ways and still remain within the scope of the invention.

The present embodiment of the invention has been disclosed merely for the purpose of exemplification, since in actual practice it attains the features of advantage enumerated as desirable in the statement of the invention and the above description.

It will be apparent that changes in the details of construction, and in the combination and arrangement of parts may be resorted to, without departing from the spirit or scope of the invention as hereinafter claimed or sacrificing any of its advantages.

Having thus described my invention, what I claim as new is:

15 A mail box having a spring actuated door, an L-shaped extension disposed adjacent the free edge of the door, a spring catch having a lateral end portion anchored to one wall of the box and having a free end portion disposed in spaced parallelism to said one wall and provided with means engageable with said L-shaped extension for normally retaining the door in a closed position, a plunger slidable through said one wall of the box and 25 having its inner end normally spaced from the last referred to end portion of said spring catch, a spring secured intermediate its ends to the outer end of said plunger, said spring having opposite end portions fixed to a suitable support remote from said one wall of the mail box, and having at its intermediate portion normally flexed outwardly from the support for normally urging said plunger in a direction away from said last mentioned 30 35 end portion of said spring catch.

In testimony whereof I have affixed my signature.

DAVID QUINN.
